CLAIM

The ornamental design for a base for fabric securing system, as shown.

DESCRIPTION

FIG. 1 is a perspective view of a base for fabric securing system showing my new design;

FIG. 2 is a front elevation view thereof;

FIG. 3 is a rear elevation view thereof;

FIG. 4 is a right side elevation view thereof;

FIG. 5 is a left side elevational view thereof;

FIG. 6 is a top plan view thereof; and,

FIG. 7 is a bottom plan view thereof.

The broken lines showing portions of the base for fabric securing system form no part of the claimed design.

1 Claim, 7 Drawing Sheets
